MULTIPLE COIN SELECTOR

Robert M. Foushee and John Gottfried, St. Louis,
Mo., assignors to National Rejectors, Inc., St.
Louis, Mo., a corporation of Missouri

Application May 21, 1947, Serial No. 749,524

3 Claims. (Cl. 194—97)

1

This invention relates in general to coin separators and slug detection devices and more particularly to an automatic device for separating and testing coins of a plurality of pre-determined denominations subsequent to deposit in a single entry. Previous multiple coin devices of this general character were complicated in structure and required an exceedingly precise adjustment of certain abutments and the like for proper operation and because of their complicated and sensitive nature, cleaning and servicing required a high degree of skill and care. Previous rejectors also required precise positioning in coin machines in order to operate in a normal prescribed manner which position could not necessarily be maintained because of the portable nature of the coin machines.

This invention provides a structure including a combination of elements which overcome the above objection by the use of a new means for providing pre-determined adjustment of the magnetic testing fields and simple unobstructed runways which are easily serviced and cleaned. The new means for adjustably positioning the magnets with reference to their respective runways minimizes the necessity for accurate positioning of the separator in coin machines and constitutes one of the objects of the invention.

A further object of the invention is the provision of a novel means for scavenging all coin passageways simultaneously responsive to the rotary movement of a single element.

A further object of the invention is the provision of magnetic testing passageways having smooth plane surfaces adjacent to the face of the coin without the presence of magnetic pole pieces which eliminates the accumulation of magnetic particles and other debris.

A further object of the invention is the provision of dual book-like gates for the convenient opening and servicing of the device.

Another object of the invention is the provision of a gravity operated means for locking a weight-testing cradle when the device is tilted beyond its operating position and for also locking a second weight-testing cradle against rotation by an undersize coin.

These and other objects in one embodiment of the invention are described and shown in the following description and drawings in which:

Fig. 1 is a side elevation of the device;

Fig. 2 is a side elevation same as Fig. 1 with parts removed;

Fig. 3 is a reduced size side elevation of Fig. 2 with parts removed;

2

Fig. 4 is a side elevation of the device opposite that shown Fig. 1;

Fig. 5 is a fragmentary side elevation shown Fig. 4 with parts removed;

Fig. 6 is a fragmentary inside rear elevation of the device shown Fig. 1;

Fig. 7 is a cross sectional end view taken thru section line 7—7, Fig. 4;

Fig. 8 is a fragmentary end view taken thru section line 8—8, Fig. 4;

Fig. 9 is a fragmentary cross sectional view taken thru section line 9—9, Fig. 4;

Fig. 10 is a diagrammatic view showing the paths of coins of largest diameter thru the device;

Fig. 11 is a diagrammatic view showing the paths of coins of medium diameter thru the device;

Fig. 12 is a diagrammatic view showing the paths of coins of smallest diameter thru the device.

The combination coin sorter and slug rejector hereinafter described is adapted to receive and sort acceptable coins of three diameters and to reject all other coins, slugs, tokens and the like therefrom. For the purpose of simplifying the description it is assumed that this particular embodiment of the invention is adapted for use with United States nickels, dimes, and quarters. The entire separator is constructed on and around a non-magnetic main frame 1 which frame is shown in all figures of the drawings and serves as a housing and supporting member for all elements.

An outer gate 2 best shown Figs. 1 and 6 is pivotally suspended to frame 1 on ears 3—3 integral with the frame and ears 4—4 integral with the gate and having a hinge pin 5 therethru. A coil spring 6 positioned around pin 5 and having its ends bearing against the frame 1 and gate 2 respectively as shown, normally urges the gate 2 in spaced relation with the inner surface of frame 1. A single entrance passageway 7 is formed between gate 2 and the frame 1 when the formed tongue 8 of gate 2 is in contact with the inside surface of frame 1.

Referring to Figs. 1, 4 and 6, a counter-weighted cradle 9 is pivotally suspended on gate 2 by pivot 10 secured to the gate. The cradle 9 has a pair of spaced projections 11—11 freely extending thru apertures 12 and 13 in gate 2 and corresponding apertures 14 and 15 in the frame 1. The distance between the projections 11—11 will permit the free passage therebetween of all coins having diameters less than that of the largest coin to be tested, namely a United States quarter.

55 A counter-weight 16 integral with the cradle 9

normally urges the cradle in position shown Fig. 1.

Referring to Fig. 6 a pendant 17 is pivotally suspended to the inside of gate 2 on pivot 18 and has a lateral projection 19 extending thru aperture 20 in the gate 2.

Referring to Fig. 1 this projection 19 will engage the projecting end 21 of the cradle 9 and prevent the latter's rotation when the frame 1 is shifted excessively counterclockwise from its normal vertical position thus a coin suspended in the cradle 9 will not be deflected to a testing passageway unless the frame is in its approximate pre-determined vertical position. When the frame 1 is shifted in a clockwise direction from its normal position the pendant projection 19 will not engage the projecting end 21 of the cradle but since this position will impart excessive velocity to the deposited coin it will be rejected by other means in the device. The pendant 17 also serves another purpose to be herein-after described.

A second counter-weighted cradle 22 pivotally mounted on gate 2 by pivot 23 has projections 24-24 extending thru apertures 25-25 in the gate 2. The distance between the projections 24-24 will permit the passage therebetween of all coins having a diameter less than that of the second size acceptable coin, namely the United States nickel.

Referring to Fig. 6 it is apparent that the lower end of the pendant 17 will normally prevent the rotation of cradle 22 because of interference with the upper projection 24; however when a coin of proper weight descends between projections 11-11 of cradle 9 it will move pendant 17 sufficiently far to permit the coin to straddle projections 24-24 of cradle 22. When a coin of proper diameter but insufficient weight is deposited, the coin will be prevented from straddling the projections 24-24 by virtue of interference by pendant 17. Thus the coin will remain suspended between an outer surface of pendant 17 and divergent edge 28.

A runway plate 26 is secured to the inside surface of gate 2 and provides a runway 27 along its upper edge for conducting large size coins for further testing. A divergent edge 28 sloping in opposite direction provides a runway for conducting all coins of lesser diameter than a quarter toward the cradle projections 24-24. A second runway plate 29 has a sloping upper edge forming a runway 30 for conducting nickel size coins in proper direction for further testing. A divergent edge 31 sloping in opposite direction provides a guide for conducting all coins of lesser diameter than a nickel to sloping ledge 32 which is formed in gate 2 as shown for laterally displacing to a laterally disposed passageway all coins of lesser diameter than a nickel for further testing.

Referring to Fig. 1 a movable dislodging plate 33 is pivotally retained to gate 2 by integral projections 34-34 extending into mating apertures in the gate. Leaf spring 35 secured at one end to gate 2 by rivet 36 normally urges the plate into position shown Fig. 1 against the surface of a flange 37 to be herein-after described. Dislodging projections 38 and 39 and deflecting projection 40 are integral with the plate and normally extend at right angles thru clearance apertures in the gate 2. The projections 38 and 39 are normally retracted from the passageway between the gate 2 and the inside surface of the

main frame 1. The normal position of projections 38, 39 and 40 are also shown in Fig. 6.

Referring to Figs. 2 and 6 a second, paramagnetic, gate 41 having its upper portion normally positioned directly behind and in parallel spaced relation with gate 2 is pivotally mounted by integral ears 42-42 to pin 5 and since the upper portion of gate 41 is between gate 2 and the main frame it is also normally urged toward the inside surface of frame 1 by the influence of spring 6. A stop pin 43 secured to an ear 44 in the upper end of the plate 41 is positioned as a stop for holding the plate 41 in parallel spaced relation with the inside surface of frame 1. The inside surfaces of gates 2 and 41 shown Fig. 6 lie in the same plane by virtue of an off-set 45 in gate 2. Slots 46 and 47 in gate 41 are provided as clearance apertures thru which runway plates 26 and 29 normally project.

Referring to Fig. 4 a counter-weighted lever 48 pivoted on rivet 49 in frame 1 has a projection 50 extending thru apertures 51 in frame 1 and gate 41. This projection 50 normally extends into the space between the inner surface of frame 1 and gate 41 in the path of the quarter passageway.

Referring to Fig. 6 an opening 52 is provided in gate 41 for purposes to be herein-after described. An off-set laterally extending ear 53, Fig. 6, is formed in gate 41 for the purpose of laterally displacing acceptable quarter coins into the quarter acceptance passageway 54 shown Fig. 7. Holes 55-55 in plate 41 provide a clearance for screws 56-56 which screws retain a nickel testing anvil 57 shown Figs. 2 and 3 to the inside surface of frame 1. Thus the gate 41 may assume its normal parallel spaced relation with reference to the inside surface of frame 1.

A rejection chute 58, Fig. 1, is secured in spaced relation to the outer surface of gate 41 by means of screws 59 in gate 41. When gate 2 is in normal position as shown Fig. 1 the sloping ledge 32 in gate 2 will be positioned slightly above a mating ledge 60 projecting inwardly from aperture 61 in the frame 1 better shown Fig. 9. Thus coins having a diameter less than a nickel descending between cradle projections 24-24 will be projected thru aperture 61 to the dime runway between the outside surface of plate 136 of frame 1 and the inside surface of gate 62 shown Fig. 4. A paramagnetic plate 136 shown Figs. 4, 8 and 9 illustrates an auxiliary plate secured adjacent to frame 1 for providing a magnetic keeper for the dime testing magnet to be herein-after described. Gate 62 is provided with ears 63-63 which correspond with ears 64-64 in the frame 1 thru which pin 65 provides a hinge. Thus it is apparent that the gate 62 can be swung outwardly about the pin 65. A retainer bracket 66 also pivoted about pin 65 is provided with an off-set ear 67 which acts as a stop when the ear is in contact with the end of pin 126 which is secured to frame 1. A double coil spring 68 positioned about pin 65 having its looped portion bearing against frame 1 and its two ends bearing against bracket 66 and gate 62 respectively serves to urge the gate in its normal operating position. A right-angled projection 69 integral with bracket 66 normally projects into a clearance aperture 70 in the gate but not into the passageway between the gate 62 and the frame 1. A counter-weighted cradle 71 pivoted to gate 62 on pivot 72 is provided with two integral spaced projections 73 and 74 which extend thru clearance openings in gate 62 into the passageway between the gate and frame 1.

A projecting ear 75 integral with gate 62 serves as a pivotal mounting for roller 76 the action of which will be hereinafter described.

Referring to Figs. 4 and 5 a spacer plate 77 is secured to the lower portion of gate 62 and the upper surface thereof serving as a runway 78. This plate also serves as a spacer between the gate 62 and the outer surface of the plate 136.

Referring to Fig. 4, the dime testing passageway is formed by plate 80, which is spaced in parallel relation to the outside surface of frame 1 by spacer plate 87 and secured thereto by rivets 88 extending through plate 80, spacer plate 87 and frame 1. Magnet retainer plate 80a is riveted to the outside surface of plate 80 and has integrally formed therein a cover 82 for completing the quarter acceptance passageway 54, also shown Fig. 7.

Referring to Fig. 4 an abutment lever 84 is pivoted to the plate 80 by pin 85 and has an integral projection 86 extending thru an aperture in the plate into the passageway between the plate and the frame 1.

Referring to Fig. 5 the projection 86 is centrally positioned above a spacer plate 87 which plate is secured to the frame 1 by rivets 88. The two upper edges of the plate serve as an acceptance runway 89 and a rejection runway 93 for coins of smallest diameter. When coins are rejected they travel out of the reject passageway 131 as shown by arrow.

Referring to Figs. 3 and 6 a guide plate 92 integral with gate 41 forms a runway 93 along its upper edge to provide a runway for acceptable nickel coins. An inwardly formed projection 94 is adapted to extend into a clearance aperture 95 in frame 1, Fig. 2, and serves the purpose of by-passing coins to be hereinafter described. Formed abutment 99 is provided to extend against the inner surface of the frame 1 to properly position gate 41 with respect to the inner surface of frame 1.

An abutment pin 96 is secured to frame 1, Fig. 3, and serves the purpose of separating five-cent coins after impact against anvil 57. A plate 97 is positioned on the outer surface of gate 41 to provide an upper edge 98 as a coin runway to be hereinafter described for rejecting non-acceptable coins of nickel and quarter size.

Referring to Figs. 4 and 7 a housing 100 serves as a positioning means for a two-pole permanent magnet 101 mounted therein. The pole faces of the magnet are positioned in counterbore 102 in the main frame 1. The housing is provided with two elongated slots 103 for adjustably positioning the magnet about its center. Screws 104 are adapted to lock the magnet in adjusted position to plate 105 which plate is integral with frame 1. Magnet 101 is intended to test the conductivity properties of the quarter size coin.

A second housing 106 contains a second permanent magnet 107 and is adjustably retained to plate 105 in counterbore 108 in frame 1 by screws 104 in the same manner as the first-mentioned magnet. Magnet 107 is utilized to test the conductivity properties of the nickel size coin.

A third housing 109 is adjustably secured to retainer plate 80a by screws 104 and contains a magnet 110 positioned in counterbore 111 in frame 1. Magnet 110 is used to test the conductivity properties of the dime size coin.

All magnets like magnet 101, Fig. 7, have their pole faces in contact with the inner surface of a counterbore providing a pre-determined thick-

ness of non-magnetic metal between the pole faces and the coin passageway, and a paramagnetic plate in spaced relation to the pole faces serving as one wall for the coin passageways and also as a keeper for the magnets thus providing a pair of magnetic field zones across the air-gap in each passageway.

Referring to Fig. 3 an aperture 112 is provided in the main frame 1 for discharging quarter size coins into acceptance passageway 54 behind cover 82, Fig. 4.

Referring to Figs. 3 and 7 a portion of the plate 80 is formed into a sloping tongue 113 to assure the travel of acceptable quarters into the acceptance passageway shown by arrow.

It is to be noted in Fig. 3 that the pole faces of magnets 101 and 107 do not project thru the surface of the plate and hence avoid the accumulation of debris thereto. It is to be further noted that Fig. 7 illustrates the relative position of the magnet 101 with relation to the gate 41 which being paramagnetic material becomes a keeper for both magnets 101 and 107 shown Fig. 4.

Because it is possible for underweight and magnetic coins to become suspended in the cradles or adjacent the testing magnets means is provided for releasing or scavenging suspended coins by imparting motion to a single element which movement will clear all suspended coins from the device as hereinafter described.

Referring to Fig. 1 a disc 114 responsive to rotation is secured to a shaft 115 which shaft is journaled thru frame 1 as shown. Integral with the shaft 115 is a wiper blade 116 adapted to sweep across the inside surface of the frame 1 adjacent to the magnets 101 and 107 when the shaft 115 is rotated as shown in dotted lines, Fig. 3. A stop pin 117 integral with the wiper blade projects into a slot 118 for limiting the motion of disc 114 and the blade 116. It is to be further noted that when the wiper blade 116 is in the position shown in dotted lines, Fig. 3, that any coins deposited in the entrance passageway 7 will strike the outer edge of the wiper blade and descend into the reject passageway.

Referring to Fig. 4 a lever 118 is pivotally mounted at one end to disc 114 by pin 119. This lever is guided by a bracket 120 integral with plate 105. A camming projection 121 integral with lever 118 is adapted to engage and move outwardly roller 76 when disc 114 is rotated. A spring 122 secured at one end to an ear 123 in the disc 114 and having its opposite end secured to a projection 124 on the lever 118 serves to urge the lever 118 and the disc 114 into position shown Fig. 4.

Referring to Fig. 5 a second wiper blade 125 is pivotally mounted to pin 126 secured to the main frame and is adapted to sweep across the surface of frame 1 against the restraining action of spring 127 which spring has one end engaged with the wiper blade 125 and its opposite end engaged to fixed bracket 120 on cover assembly 80. A projection 128 of lever 118 is adapted to contact the outer edge of wiper blade 125 and move the wiper blade against the action of spring 127 to position shown in dotted lines when the lever 118 is moved to its dotted position by rotation of the disc 114. Thus when a coin is suspended in the zone of the field of magnet 116 it may be projected into the reject passageway 131 by rotation of disc 114.

Furthermore any coins of dime size deposited when the wiper blade 125 is in its displaced position will be deflected directly into the reject

passageway by virtue of the off-set end of the wiper blade.

Referring to Figs. 4, 8, and 9 it is apparent that when the camming projection 121 engages the roller 76 the first movement will move gate 62 outwardly from the main frame against the restraining action of spring 68. Thus a coin straddling the projections 73 and 74 of the cradle 71 will be dislodged therefrom by projection 69 of retainer bracket 66 directly into the reject passageway. It is also to be noted that further movement of the lever 118 will continue the outward movement of gate 62 by virtue of cam 121 and roller 76 and ultimately move retainer bracket 66 sufficiently far outwardly to dislodge any debris retained between the gate 62 and the main frame 1 as illustrated by dotted lines, Fig. 8.

Referring to Figs. 1 and 4 a projecting cam 132 integral with gate 2 normally projects thru an opening 133 in frame 1 in the path of a roller 134 which roller is pivotally secured at right angles to the ear 123 by stud 135. When the disc 114, Fig. 4, is rotated in the direction shown by arrow the roller 134 will cam against a sloping surface of the projecting cam 132 and move gate 2 outwardly from the frame 1. This first movement will cause the projections 38 and 39 of the plate 33 to dislodge any coin suspended upon the cradles 9 and 22 where they will fall by gravity into the rejection chute 58. The projection 40 normally projects into the runway between gate 2 and the frame 1, and serves as a guide to direct coins into the rejection chute 58. Further rotation of disc 114 will continue the movement of the gate 2 outwardly about pin 5 and cause the plate 33 to move outwardly away from flange 37 of gate 41, to completely clear the passageway between the gate 2 and the frame 1 of any debris suspended therein.

It is further to be noted that the gate 2 may be manually opened against the restraining action of spring 6 and thus expose gate 41 as shown Fig. 2 which gate may also be opened for service by overcoming the magnetic attraction between the gate and magnets 101 and 107 positioned in the opposite side of the frame 1.

One of the important features of the device is the means provided for rotating the magnets 101, 107 and 110 about their horizontal neutral axes. It is well-known that since the magnets have two poles facing the gate or keeper 41 that a concentrated magnetic field will span in two zones the space between the pole faces and the keeper. Each zone of magnetic field for each magnet will be of opposite polarity, namely, north and south, thus the eddy currents set up in a coin passing both zones of a single magnet will have introduced therein eddy currents of opposite polarity, thus by rotating the magnet about its horizontal axis a coin traversing its two zones of magnetic field will have a greater or lesser degree of eddy currents of opposite polarity set up therein. This phenomenon provides for an extremely sensitive adjustment of trajectory for a coin of given conductivity. It is to be noted that rotating the magnet about its horizontal axis does not vary the total intensity of the magnetic field in the passageway.

In operation and referring to Fig. 10 under the assumption that an acceptable U. S. quarter is deposited in the entrance passageway 7 it will descend along runway 129 and straddle projections 11 of cradle 9 shown Fig 1 and since the coin is of acceptable weight the cradle will rotate and deposit the coin on the runway 27 of the plate

26. By the action of gravity after leaving the lower edge of runway 27 it will traverse the adjustable magnetic field of magnet 101 and under the assumption that the coin has the proper conductivity its forward velocity will be reduced and the coin will fall in a free trajectory indicated by the right hand line of travel, Fig. 10, whereupon its edge will impinge upon projection 50 in such a position as to deflect the coin in the direction of the acceptance passageway where it will be displaced laterally by off-set ear 53 in gate 41 over a mating sloping tongue 113 shown Figs. 3 and 7 where it will descend into acceptance passageway 54 which lies between cover 82 and the cover assembly 80.

Since the magnet 101 is adjustable generally about its center it is possible to adjust the magnet to provide a sensitive pre-determined deflecting influence upon a coin of known properties so as to separate by means of abutment 50 coins having slightly different conductivity.

Assuming a coin having slightly greater conductivity than that of an acceptable coin is deposited in entrance passageway 7 its initial action will be the same until it traverses the magnetic field of magnet 101. At this point the coin, because of its greater conductivity, will lose velocity at a more rapid rate than an acceptable coin and descend in the left hand path indicated to impinge upon the abutment 50 in a different position to cause the coin to descend in the left hand path whereupon it will be deflected laterally from its normal path by projection 94 to the upper edge 98 of plate 97 where it will roll by gravity directly into the reject passageway 91.

Assuming that a coin of proper diameter but underweight is deposited in entrance passageway 7 it will straddle projections 11-11 of the cradle and be thereby suspended which will require a rotation of the disc 114 in the direction shown to dislodge the coin from the projections 11-11 by the action of elements previously described whereby it will fall by gravity to divergent edge 28 of plate 26 and thence directly to the reject passageway 91.

In the event that a paramagnetic coin is deposited in entrance passageway 7 and descends along runway 27 it will be attracted and arrested in the zone of the magnetic field of the magnet 101 and will require movement of the disc 114 in the direction shown by arrow which movement will cause wiper blade 116 to deflect the coin into reject direction where it will descend into the reject passageway 91.

Referring to Fig. 11 in operation and assuming that an acceptable U. S. nickel is deposited in the entrance passageway 7 it will descend along entrance runway 129 thru the space between projections 11-11 of the cradle 9 and impinge upon divergent edge 28 and being of proper weight will move pendant 17 shown Fig. 6 sufficiently far where it will further descend and straddle projections 24-24 of cradle 22 better shown Fig. 1, where it will cause the cradle to rotate and deposit the coin on the runway 30 of plate 29 where it will further descend traversing the magnetic field of magnet 107 where its velocity will be reduced in proportion to its conductivity and being acceptable will follow the right hand path indicated to impinge upon the edge of anvil 57 where it will rebound over abutment pin 96 to runway 93 formed in plate 92 where it will descend into the nickel acceptance passageway 130.

Assuming that a coin of proper weight and diameter but having greater conductivity and/or

less resilience it will descend the same as previously described into the field of magnet 107 whereby its free trajectory path will change in accordance with its conductivity and in rebounding from the anvil 51 it will not attain sufficient velocity to project over the abutment pin 96 but on the contrary will be by-passed by contact with projections 94 forward of gate 41 and then descend along the upper edge 98 of plate 97 directly into the reject passageway 91.

Assuming that a coin of nickel diameter but underweight is deposited in entrance passageway 7 it will descend thru projections 11-11 of cradle 9 and then be suspended between divergent edge 28 and the pendant 17 shown Fig. 6 which will require movement of the disc 114 to release the suspended coin directly into the rejection passageway 91.

A further important feature of the pendant resides in its operation in preventing coins having a diameter less than that of a quarter from entering the quarter passageway. Normally such coins, for example a U. S. penny, will descend between the projections 11-11 of cradle 9 and be directly rejected. Under normal velocity conditions the inner projection 11 of cradle 9 prevents these smaller coins from entering the quarter passageway. The first of a series of coins, under certain conditions, deposited in rapid succession will impinge upon the inner projection 11 of cradle 9 with sufficient velocity to rotate the cradle 9 and permit subsequent coins to enter the quarter passageway where again under certain favorable velocity conditions they may be accepted as quarters. This undesirable action is entirely prevented by pendant 17 inasmuch as the first smaller diameter coin deposited will descend between projections 11-11 of cradle 9 and strike against the inner edge of the pendant 17 and move the pendant to approximately the position shown in dotted lines, Fig. 6. This movement will position the pendant projection 19 in the path of the projecting end 21 of cradle 9 and thus prevent its rotation by a subsequent coin, thereby preventing any subsequent undersized coins from entering the quarter passageway.

Assuming that a coin of nickel dimensions and weight but having paramagnetic properties is deposited in entrance passageway 27 it will descend in the manner of an acceptable coin until it reaches the magnetic zone of influence of magnet 107 where it will be retained to the inside surface of frame 1. Then it will require the rotation of disc 114 to move wiper blade 116 to dislodge the coin directly into the reject passageway via the general path described by other non-acceptable coins.

Referring to Fig. 12 and assuming that an acceptable dime is deposited in the entrance passageway 7 the coin will first descend along entrance runway 129 thru cradle projections 11-11 and impinge upon divergent edge 28 and pass thru the space between the edge 28 and the pendant 17 thru cradle projections 24-24 where it will be deflected by divergent edge 31 of runway plate 29 where it will be projected laterally by the sloping edge 32 and its mating ledge 60, better shown Fig. 9 whereupon it will strike projection 73 and move cradle 71 in a counter-clockwise direction until the coin straddles both projections 73 and 74. The cradle will then be overbalanced and will rotate clockwise to deliver the coin to runway 78 of plate 77 whereupon it will traverse the magnetic field of the magnet 110.

Since the coin has the proper conductivity it

will move in a free trajectory as shown by right hand path, Fig. 12, and strike the projection 86 in a position to cause the coin to move downwardly along runway 90 of plate 87 and thence into the dime acceptance passageway 83.

In the event a coin of higher conductivity than that of an acceptable dime is deposited in entrance passageway 7 it will follow the same course previously described except when it traverses the magnetic field of magnet 110 it will be slowed sufficiently to assume a path to the left of that of an acceptable coin as shown and strike projection 86 at a position whereby the coin will be deflected to descend runway 89 of plate 87 into rejection passageway 131.

It is now apparent that when a coin having the same diameter as a dime but underweight is deposited in entrance passageway 7 it will fall in a normal course until it strikes projection 73 of cradle 71 and not having sufficient kinetic energy to rotate the cradle will remain suspended thereon.

Under these conditions and referring to Fig. 4 the rotation of disc 114 will open gate 62 and permit projection 69 of bracket 66 to dislodge the suspended coin from the cradle projection 73 directly into the rejection passageway 131. Likewise when a paramagnetic coin is suspended in the zone of the magnet 110 the operation of disc 114 will move wiper blade 125 to dislodge the suspended coin directly into the reject passageway 131.

It is also apparent that the adjustable rotational positioning of magnet 110 like the other previously described magnets will sensitively influence the path of travel of a coin traversing its field by presenting more or less lines of magnetic force to be traversed therethru by the coin. Hence the use of the rotationally adjustable magnets greatly increases the sensitivity of the device in separating coins having slightly different conductivity properties.

Having described our invention, we claim:

1. In a coin separator a frame means including an entrance passageway for conducting edgewise gravity controlled coins, a testing passageway in said frame connecting said entrance passageway, a runway in said frame positioned in said testing passageway having one end adjacent said entrance passageway, a cradle means pivotally mounted in said frame means adjacent said entrance passageway, said cradle means having a pair of projections extending into said entrance passageway for straddling a coin of acceptable diameter and weight and transferring said coin to said runway, one of said cradle projections normally blocking the entrance of said testing passageway, a pendant pivoted for rotation on said frame means and in said entrance passageway, the axis of rotation of said pendant positioned parallel to the axis of rotation of said cradle and spaced from said runway, a locking projection extending from said pendant normally clearing the path of movement of said cradle means whereby the descent of a coin of less than acceptable diameter and of proper weight in said entrance passageway will by-pass between said cradle projections and impinge said end of said runway and one edge surface of said pendant and move said pendant to position its said locking projection into the path of movement of said cradle means for preventing movement thereof and retaining the said one of said projections in blocking position in the entrance of said testing

passageway to momentarily prevent a subsequent coin from entering said testing passageway.

2. In a coin separator of the character described frame means including an entrance passageway for conducting edgewise gravity propelled coins, a testing passageway connecting said entrance passageway having a sloping runway therein, cradle means pivotally mounted on said frame means adjacent to said entrance passageway, said cradle means having a pair of projections extending into said passageway for transferring acceptable coins descending in said entrance passageway to said runway, a pendant pivotally suspended on said frame means on an axis parallel to the axis of movement of said cradle means and positioned above said projections, a portion of said pendant normally positioned in the path of movement of one of said projections to prevent normal movement thereof, a fixed abutment on said frame in said entrance passageway above said cradle and adjacent to one edge of said pendant, whereby a coin of acceptable diameter descending in said entrance passageway will impinge said abutment and the said edge of said pendant and move said pendant out of the path of the said one of said projections to permit said coin to descend and straddle said pair of projections and permit movement of the said cradle to transfer said coin to said runway for further descent in said testing passageway and whereby a coin of lesser diameter and of improper weight descending in said entrance passageway will not move said pendant sufficiently far to permit rotation of said cradle means and thereby remain suspended on said abutment the other of said projections and on the said edge of said pendant.

3. In a coin separator of the character de-

scribed a diamagnetic frame means, a plane inside surface in said frame means forming one inner vertical wall of a coin testing passageway, a paramagnetic gate pivotally mounted at one end to said frame means and normally positioned in parallel spaced relation with said vertical wall forming a passageway therebetween, a sloping runway in said frame positioned in said passageway for conducting coins in a predetermined path, a permanent magnet secured on the outer side of said frame means for rotatable adjustment about an axis normal to said path, said magnet having its north and south poles symmetrically positioned about said axis and having the faces of said poles parallel with said passageway providing two zones of magnetic field of opposite polarity across said passageway to said gate whereby a coin descending in said passageway on said runway will traverse more or less of each of said zones of magnetic field depending upon the adjustment of said magnet about its axis to influence said descending coin from said runway in a predetermined free vertical trajectory.
